UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

FLEXIBLE-CONNECTION BOX.

1,307,683.

Specification of Letters Patent. Patented June 24, 1919.

Application filed November 20, 1917. Serial No. 202,956.

To all whom it may concern:

Be it known that I, WILLIAM W. LASKER, a citizen of the United States, residing in borough of Brooklyn, in the county of Kings and State of New York, have invented certain new and useful Improvements in Flexible-Connection Boxes, of which the following is a specification.

This invention relates to punched card tabulating machines and has for its objects to provide connections between the setting members of the analyzer and the control members of the accounting machine which will permit records to be printed in columns of practically any desired arrangement, sequence or distance apart on the printed page practically without any regard to the arrangement, sequence or distance apart of the columns or zones of perforations on the perforated card.

To this end, I have provided flexible push cables each having an inner wire having detachable connection with the setting pins of the analyzer and the control or stop pins of the accounting machine. Said wires have their ends frictionally received in tubular analyzer setting pins and tubular control pins on the accounting machine, and are guided to such pins by suitable guide tubes.

It is, of course, understood that any other convenient means and connections may be used which will accomplish the same function; and while herein, I have described minute details of my device, it is obvious that the invention is not limited to these, as the details of construction and combination may be greatly varied without departing from the spirit and scope of the invention as claimed.

In the accompanying drawing showing by way of example one of many possible embodiments of the invention.

Figure 1 is a side elevation of a card-operated printer tabulator embodying my new invention;

Fig. 2 is an elevation showing the flexible connections connecting the sets of setting pins with sets of stop-pins of the accounting machine;

Fig. 3 is a sectional view taken on the line 3—3 of Fig. 2;

Fig. 4 is an enlarged fragmental sectional view taken approximately on the line 3—3 of Fig. 4;

Fig. 5 is a fragmental horizontal sectional view taken on the line 5—5 of Fig. 4;

Fig. 6 is a side face elevation of the lower part of one of the stop pins of the accounting machine;

Fig. 7 is an edge view of the same, and 60

Fig. 8 is a central vertical sectional view of one of the guide tubes for guiding the end of the central wire of the flexible push card.

Referring more particularly to the drawings,—Fig. 1 shows my invention applied to 65 a perforated-card-operated printer tabulator comprising a main-frame A, an accounting machine B, and a magazine C, from which perforated cards are fed to between the analyzer plates 10. All of the parts just mentioned are similar in construction and operation to the well known printer-tabulator machines, of which an example is shown in the patent of James Powers No. 1,245,503, issued Nov. 6, 1917, and said parts are therefore not shown or described in detail herein. 70

As is well known, the cards are fed from the magazine between the analyzer plates 10, and a pin box below said plates rises until pins therein finding perforations in the 80 cards, pass upwardly through such perforations and push upwardly setting pins 11 (Fig. 3) which in turn cause upward movement of stop pins 12, as will be explained, thus controlling the position of accumulator 85 segments and type segments of the accounting machine in the well known manner. Heretofore the pins 11 and 12 have been formed of one mechanically continuous rod of which the upper part was usually offset 90 from the lower part so that sets of type segments of the machine could be spaced distances apart so that the columns of figures printed by the accounting machine would be spaced much farther apart than were the 95 corresponding columns or zones of perforations of the perforated cards.

In such machines the successive arrangement of the printed columns was the same as that of the zones of the card and this arrangement could not be changed. With the present invention, however, provision is 100

made for connecting any setting pin 11 with any desired stop pin 12; and this arrangement which constitutes the principal feature of the present invention will now be described.

Mounted upon opposite sides of the main frame A are a pair of cheek plates 14 on which are mounted end pieces 15 (Fig. 2) to which are secured the supporting bars

- 10 16 provided with transverse slots 18, (Fig. 5) in which are received the reduced ends 19 of cross bars 20, provided with side recesses 21 forming seats in which are received the intermediate reduced portion 22 (Fig. 8) of the upper and lower guide tubes 24. Each of said seats is closed by an adjacent cross-bar 20, thereby holding the guide tube in place.

Said cross-bars 20 are removably held in place by means of a plurality of retaining plates 25 engaging the outer face of said supporting bars 16 and provided with a lip 26 engaging the reduced ends of the cross bars and holding them in place.

- 25 The setting pins 11 and the stop pins 12 are made tubular in form, and are connected by the flexible push cables 28 comprising an outer casing 29 (Fig. 4) and inner wires 30 projecting from the casings at opposite ends and passing through said upper and lower guide tubes 24 and into the bores of the pins 11 and 12 in which said ends are held by friction or by any suitable means. The pins 11 and 12 are slidably held in alignment with the guide tubes 24 by means of sets of inner and outer upper perforated guide plates 31 and 32 and similar sets of lower guide plates 34 and 35. Each guide plate is provided with an angularly 40 bent portion 36 placed adjacent to the outer face of the retaining plate 25. Each angularly bent portion 36 is provided at its edge with a cutaway portion 38 giving access to the screw 39 holding the retaining plate 25 against the supporting bar 16. The guide plates themselves are held in place by means of screws 40 passing therethrough and through a cutaway portion 41 in the retaining plate 25. It will therefore 45 be seen that when the screws 40 relating to any set of guide plates and retaining plates are loosened slightly, the retaining plate 25 may be raised without removing the guide plates, thus permitting the cross bars 20 to be raised from the transverse slots 18, thus permitting the wires 30 and their associated guide tubes to be removed from association with any set of setting pins 11 or stop pins 12, the stop pins 12 being raised to permit the raising of the guide tubes.

In order to provide means for limiting the downward movement of the stop pins and the setting pins 11, these pins, which are tubular in form, have a flattened intermediate

part 44, which causes the formation of the projecting shoulders 45, which engage upon the upper face of the inner upper guide plate 32 or the lower outer guide plate 35.

The manipulation and operation of the flexible connections 28 are obvious from the foregoing, and need now be described only briefly as follows:—

When it is desired to form a considerable space between printed columns corresponding to adjacent zones of the perforated card, it is only necessary to loosen the screws 39 and 40 of the guide plates of the setting pins or stop pins to be adjusted, after which the wires 30 of the corresponding flexible cables may be removed together with the guide tubes 24, the lower ends of the wires 30 being movable to association with the zone of which the record is to be printed, while the upper ends of the wires 30 are movable to association with the stop pins controlling the type segments which will print column of figures on the desired part of the sheet on which the figures are to be printed.

The flexible cables may be of different lengths and of any length desired, so that it might even be possible to have the records from the first zone of the perforated card printed in the last column of the page; and it will be possible to reverse the order or rearrange in any manner desired the columns of records corresponding to the zones of perforations. As will be obvious, it is not necessary that the flexible connections be transferred in sets of several columns since it is easily possible to print single columns, spaced far apart, from any corresponding number of columns on the perforated card, whether these columns of perforations be adjacent to each other or not.

I claim as my invention:—

1. In an apparatus of the character described, the combination of an accounting machine having control members; an analyzer having a plurality of setting members; and means whereby one of said members may be operatively connected with one of several other members.

2. In an apparatus of the character described, the combination of an accounting machine having control members; an analyzer having setting members; and means adapted to operatively connect any setting member with any control member.

3. In an apparatus of the character described, the combination of an accounting machine having control members; an analyzer having setting members; and flexible means adapted to operatively connect any setting member with any control member.

4. In an apparatus of the character described, the combination of an accounting machine having control members; an an-

alyzer having setting members; and flexible connections adapted to operatively connect any setting member to any control member.

5. In an apparatus of the character described, the combination of an accounting machine having control members; an analyzer having setting members; and flexible connections operatively connecting the setting members to any desired control members.

10. 6. In an apparatus of the character described, the combination of an accounting machine having control members; an analyzer having setting members; and flexible connections detachably connected to certain of said members and operatively connecting the setting members to any desired control members.

15. 7. In an apparatus of the character described, the combination with an accounting machine having stop pins; an analyzer having setting pins; and flexible push cables having relatively longitudinally movable inner and outer parts, the opposite ends of one of said parts having detachable connection with said stop pins and setting pins.

20. 8. In an apparatus of the character described, the combination with an accounting machine having stop pins; an analyzer having setting pins; and flexible push cables having relatively longitudinally movable inner and outer parts, the opposite ends of one of said parts having frictional connection with said stop pins and setting pins.

25. 9. In an apparatus of the character described, the combination of an accounting machine; an analyzer; upper and lower guide tubes and guide plates; stop pins slideable in the upper guide plates and coöperating with the accounting machine; setting pins coöperating with the analyzer and slideable in the lower guide plates; and flexible push cables of which opposite ends of one member pass through said upper and lower tubes and have detachable connection with said pins respectively.

30. 10. In an apparatus of the character described, the combination of an accounting machine; an analyzer; upper and lower guide tubes and guide plates; stop pins slideable in the upper guide plates and coöperating with the accounting machine; setting pins coöperating with the analyzer and slideable in the lower guide plates; and flexible push cables of which opposite ends of one member pass through said upper and lower tubes and have frictional connection with said pins respectively.

35. 11. In an apparatus of the character described, the combination of an accounting machine; an analyzer; a plurality of upper and lower cross bars provided with recesses; upper and lower guide tubes carried in said seats; pairs of upper and lower guide plates;

stop pins coöperating with the accounting 65 machine and slideable in the upper guide plates setting pins coöperating with the analyzer and slideable in the lower guide plates; flexible push cables having inner members passing through said tubes and having detachable connection with said pins.

12. In an apparatus of the character described, the combination of an accounting machine; an analyzer; a pair of upper supporting bars; a pair of lower supporting 75 bars; cross-bars carried by the supporting bars and provided with recesses therein; upper and lower guide tubes in said recesses pairs of upper and lower guide plates carried by the supporting bars and provided with intermediate perforations; stop pins coöperating with the accounting machine and slideable in the perforations of the upper guide plates; setting pins coöperating with the analyzer and slideable in the perforations of the lower guide plates; and flexible push cables having outer flexible casings and inner wires the opposite ends of which pass through said upper and lower guide tubes and detachably secured to said setting 80 pins respectively.

13. In an apparatus of the character described, the combination of an accounting machine; pairs of upper and lower supporting bars; cross-bars provided with side recesses and having their ends supported on said supporting bars; retaining plates engaging said supporting bars and holding the cross-bars in place; upper and lower guide tubes in said recesses; pairs of upper 95 and lower guide plates having intermediate perforations and bent end portions; screws securing said end portions and retaining plates on said supporting bars; stop pins coöperating with the accounting machine and slideable in the perforations of said upper guide plates; an analyzer; setting pins coöperating with the analyzer and slideable in the perforations of the lower guide plates; and flexible push cables having outer flexible casings and inner wires the ends of which pass through said guide tubes and are frictionally received in said setting and stop pins respectively.

14. In an apparatus of the character described, the combination of a frame; an accounting machine thereon; a pair of upper supporting bars and a pair of lower supporting bars disposed under said machine and provided with transverse slots; cross-bars having reduced ends in said slots and recesses in their sides coöperating with the adjacent bar to form seats; retaining plates disposed against the outer faces of the supporting bars and engaging said reduced ends; upper and lower guide tubes having reduced intermediate parts received in said seats; upper and lower outer and inner

- guide plates having perforations in middle parts and bent end portion; screws passing through end portions and retaining plates and securing them to the supporting bars; 5 stop-pins slidable in the perforations of the upper plate for coöperating with the accounting machine and provided with tubular lower ends; an analyzer; setting pins slidable in the perforations of said lower 10 plates for coöperation with the analyzer and provided with tubular upper ends; and flexible push cables having outer flexible casings and inner wires the ends of which respectively pass through said upper and 15 lower guide tubes and are frictionally received in said upper and lower tubular ends respectively.
15. In an apparatus of the character described, the combination of an accounting 20 machine having tubular stop pins; an analyzer having tubular setting pins; upper and lower guide plates in which said pins are

slidably mounted; and flexible push cables having an inner wire the opposite ends of which are received in said tubular stop pins 25 and setting pins respectively.

16. In an apparatus of the character described, the combination of an accounting machine having tubular stop pins; an analyzer having tubular setting pins; upper 30 and lower guide plates in which said pins are slidably mounted; and flexible push cables having an inner wire the opposite ends of which are received in said tubular stop pins and setting pins respectively; said tubular pins having a flattened inner portion 35 forming shoulders adapted to engage said guide plates to limit the movement of the pins.

WILLIAM W. LASKER.
